UNITED STATES PATENT OFFICE.

CHARLES E. McMANUS, OF NEW YORK, N. Y.

CORK-SLAB-PACKING MACHINE.

Application filed November 13, 1923. Serial No. 674,488.

To all whom it may concern:

Be it known that I, CHARLES E. McMANUS, a citizen of the United States, residing at the borough of Manhattan, in the city, county, and State of New York, have invented certain new and useful Improvements in Cork-Slab-Packing Machines, of which the following is a specification, reference being had therein to the accompanying drawings, which form a part thereof.

My invention relates to cork slab packing machines, and more particularly to a machine of this type whereby a composition formed of granular cork having a thin coating of adhesive, will be delivered in succeeding measured quantities within a mold, and each charge be properly compacted prior to the delivery of a succeeding charge. The compaction is by a direct application of uniform pressure to each charge so as to secure substantially uniform density in the entire mass of granular cork within a mold, preparatory to the final step of baking or vulcanizing the compacted mass while still within the mold for the purpose of conditioning the adhesive or binder with which the separate cork granules are thinly coated so as to firmly bond these granules together. A slab thus formed is composed of a substantially integral mass having all of the properties of natural cork with the added properties of a substantial freedom from surface or concealed voids, and possibly a higher degree of resiliency.

A machine embodying my invention is so constructed that the compaction of the successive charges of granular cork composition is by a plunger, the effective length of the succeeding strokes of which, is automatically varied to accommodate the plunger to the progressively increasing mass of the cork composition within the mold, while at the same time maintaining the same degree of pressure developed with each stroke and in relation to each charge. The actuating means for this plunger, operates thereon as to the timing of the strokes and the pressure developed during each stroke, under uniform conditions at all times, the variance in the length of the stroke of the plunger resulting from an automatically acting connection between same and the actuating means therefor which will adjust itself upon succeeding strokes, as required by the mass of

granular cork composition which may be accumulated in the mold at that time.

In conjunction with a plunger mechanism having the characteristics above referred to, I provide a measuring mechanism acting in synchronism with the plunger actuating means, whereby a charge of cork composition will be delivered to within the mold prior to each compression stroke of the plunger, this measuring device being so constructed as to not only ensure a substantially uniform quantity of the cork composition being delivered with each charge, but a substantially equal distribution of each charge in the measuring and feeding mechanism prior to its delivery to within the mold, thus avoiding any substantial variation in the volume of cork delivered to different portions of the mold.

The molds used in connection with the machine may vary from one and one-half inches or more in thickness by twenty to thirty inches in depth, and three feet or more in width, so that this effective distribution of the cork composition is highly desirable in securing that uniform density throughout all portions of the mass of cork composition compacted within the mold by a machine embodying my invention. Uniformity in the mechanical compaction of the cork, limits the degree of that readjustment of the cork particles which occurs when the mold and its contents is subjected to the heat of the baker or vulcanizer, during which treatment any slight variances in density are compensated for by the tendency of the mass of cork composition to expand, which expansion beyond the limits of the dimensions afforded by the closed molds, is prevented.

A machine embodying my invention is also so constructed that a closure plug is inserted in the open top of the mold by means of the plunger mechanism, so that with a cycle of operations including a given number of strokes of the plunger, the mold will be completely filled, and after the last charge of the cork composition has been compacted by the plunger, the next stroke of the plunger will insert the closure plug and force it into the mold in engagement with the compacted mass of cork composition under pressure, thus avoiding any space between the packed cork composition within the mold and this closure plug. The plug is firmly secured in

relation to the mold while so positioned that the displacement thereof as a result of expansion of the mass of cork composition within the mold during baking or vulcanization, is prevented.

The automatic mechanism for inserting the plug within the mold, necessitates the provision of means whereby no cork composition will be fed with relation to the mold during that stroke of the plunger which is utilized for inserting the plug in the mold, and for the automatic stoppage of the machine following this plunger stroke.

While in a machine embodying my invention the cork measuring and distributing mechanism is so constructed that no cork will be fed to the mold prior to and during that stroke of the plunger utilized for inserting the plug in the mold, the construction is such that a charge will be properly measured out and distributed during this stroke so that upon the first stroke of the plunger upon the succeeding cycle of operations, an initial charge will be delivered to the mold replacing the completely packed one, this condition being required because the failure to deliver a charge to the mold would result in an improper filling and compacting of the cork composition throughout the mold during any cycle of operations of the mechanisms of the machine.

The invention consists primarily in a cork slab packing machine embodying therein a support for a mold, a plunger adapted to enter said mold, a reciprocatory slide, means whereby said slide receives uniform reciprocatory movement, means carried by said slide and adapted to operatively engage said plunger and to impart positive reciprocatory motion thereto, means whereby the operative relation between said last named means and said plunger will be automatically varied with each stroke of said slide and said plunger, to cause a progressive decrease in the effective length of succeeding strokes of said plunger to compensate for the increasing volume of cork composition in said mold, and means delivering a measured quantity of cork composition to within said mold prior to each stroke of the plunger inwardly of the mold; and in such other novel features of construction and combination of parts as are hereinafter set forth and described, and more particularly pointed out in the claims hereto appended.

Referring to the drawings,

Fig. 1 is a view in side elevation from the left of the machine;

Fig. 2 is a plan view;

Fig. 3 is a front view with the cork composition hopper and parts appurtenant thereto and the mechanism for positioning the closure plug, removed;

Fig. 4 is a section on the line 4—4 of Fig. 3, with the cork composition hopper,

feeding mechanism and the means for positioning the closure plug, shown in their proper position;

Fig. 5 is a detail view of one of the units connecting the plunger, and the relation of these parts to the mold, the parts being shown in position preparatory to the initial, or long, stroke of the plunger;

Fig. 6 is a similar view showing the relation of parts at the completion of this initial stroke;

Fig. 7 is a view similar to Fig. 5 with the parts in their position prior to the final stroke for forcing the closure plug into the mold;

Fig. 8 is a similar view showing the relation of parts at the completion of the final stroke;

Fig. 9 is a detail view of the controlling mechanism for the feeding valve in its normal position;

Fig. 10 is a similar view showing in full lines the position of parts for effecting the stoppage of feed of the cork composition, and in dotted lines the position of parts just prior to the final stroke of the plunger with each cycle of operations of the machine;

Fig. 11 is a cross-sectional view of the mechanism shown in Fig. 9;

Fig. 12 is a section on the line 12—12 of Fig. 11;

Fig. 13 is a detail view of the mechanism for positioning the closure plug, the full lines showing the normal position of this mechanism, and the dotted lines showing the position of parts just prior to the final stroke of the plunger;

Fig. 14 is a similar view showing the position of parts when the mechanism shown in Fig. 13 has been actuated to move the closure plug into position with relation to the mold; and

Fig. 15 is a plan view of the mechanism shown in Fig. 13.

Like numerals refer to like parts throughout the several views.

In the embodiment of my invention shown in the drawings, I employ a reciprocatory slide 20 mounted upon vertical guides 21, said guides being four in number as indicated in Figs. 2 and 3. In addition to the guides 21, I provide a slideway 22 arranged substantially centrally of the group of guides 21, which co-operates with, and will ensure the desired rectilineal movement of, the slide 20.

The slide 20 receives reciprocatory movement by means of a crank wheel 23 and a pitman 24 connecting said wheel with the slide 20 in any desired manner, such as is shown more particularly in Fig. 4 of the drawings.

To ensure ease of movement of the slide 20, I provide counterweights 25 connected therewith by means of chains 26 passing over

sprocket wheels 27 mounted upon a shaft 28 adjacent the top of the machine. The counterweights 25 are guided in their movements by rods 29.

5 The crank wheel 23 is driven by means of a gear train 30 so as to secure any desired speed of, and power developed by, the slide 20, the first gear of this train being driven from any desired source of power, as a belt 10 and pulley mechanism 31, and a clutch mechanism 32 connecting this pulley with said gear train.

Forwardly of the crank wheel 23 and pitman 24, are suitable stop bars 33 above a 15 table 34 adapted to receive a mold 35. Mounted forwardly of the bars 33 is a clamp bar 36 adapted to be brought into parallel relation with the faces of the bars 33 and to hold the mold firmly in position with 20 relation to said bars by means of clamps 37 adjacent opposite sides of the machine. The clamps 37 are pivotally connected with the top bar 33 by means of pivotal links 38 so as to permit the clamps to be moved 25 into or out of the engaging relation with the clamp bars 36 when positioning the mold in the machine, or when removing it therefrom.

The slide 20 has an extension 39 projecting forwardly of the slideway 22 to a position above the vertical center of a mold 35.

The composition cork delivered to a mold 35 is compacted therein by means of a plunger head 40, the dimensions of which 35 are such as to have a free sliding fit within the cavity of a mold 35, the top of this cavity being open, and presented toward the extension 39 of the slide 20. This plunger head 40 is provided with a plurality of stems 41 slidably mounted in the extension 39, and is caused to have reciprocatory movement with said slide 20 by means of connections between said slide and said plunger, so constructed that with a constant length of stroke of said slide, the effective length of stroke of said plunger head, will be progressively decreased so as to compensate for the progressively increased volume of cork composition accumulated within a mold during each cycle of operations of the machine. In addition to causing this variation in the effective stroke of the plunger, the connections between same and the slide 20 are so constructed that the 45 full power applied to the slide will be transmitted to said plunger and cause a positive pressure upon the contents of the mold.

The connections between the plunger head 40 and the slide 20, in the form of the invention shown, consists of a plurality of bars 42 carried by said plunger head and passing through openings in the extension 39 of the slide 20. The construction of each 50 of these bars and of the parts appurtenant thereto, is identical with the other bars,

so that a detailed description of but one of such mechanisms is necessary.

The bar 42 has formed thereon, preferably upon opposite edges thereof, two sequences of ratchet teeth 43 and 44, the teeth 70 of one of these sequences of teeth being set in one direction, and those of the other being set in the opposite direction. The downward movement of the plunger 40 is imparted through the rack 43, and upward 75 movement of said plunger is imparted through the rack 44, said racks being staggered in relation to each other, the rack 43 terminating adjacent the plunger head 40 and the rack 44 terminating adjacent the 80 upper end of the bar 42.

Carried by the extension 39 of the slide 20, is an oscillatory pawl 45 having an upwardly directed stem 46, acted upon by a spring 47, having a normal tendency to force 85 said pawl into engaging relation with the rack 43. The pawl 45 in addition to its pivotal connection with the extension 39, is permitted slight reciprocatory movement to ensure the necessary engagement of this 90 pawl with succeeding teeth of the rack 43 upon succeeding strokes of the slide 20.

Also carried by the extension 39 of the slide 20 in operative relation to the ratchet teeth 44, is a pivotal pawl 48 having a 95 downwardly directed stem 49 acted upon by a spring 50, so as to normally force this pawl toward the teeth 44. Carried by the extension 39 of the slide 20 is a latch member 51 adapted to engage the pawl 48 and hold it out of the operative relation to the teeth 44 at the end of the last stroke of 100 each cycle of operations of the machine in packing each mold.

The stem 46 projects beyond the extension 39 of the slide 20 to an extent which will bring it into engagement with a plate 52 positioned on the top frame 53 of the machine as the slide 20 is approaching the limit of its upward movement, or its movement away from the mold, while the stem 49 is of a length and so positioned as to engage the plunger head 40 toward the limit 105 of the downward movement of the slide 20 and plunger 40 during the last stroke of 110 the cycle of operations of the machine in packing a mold.

The pawl 45 projects downwardly from the lower face of the extension 39 of the slide 20 while the pawl 48 projects upwardly from the upper face of said extension. 120

Each of the stems 41 is provided with an enlarged head, as 54, adapted to engage a cushioning spring 55 seated upon the top 125 of the extension 39 of the slide 20.

Above the bars 33, and forwardly thereof, is a hopper 56 adapted to receive cork composition, the outlet of which is controlled by a rotary measuring valve 57 130

adapted to be intermittently actuated in synchronism with the movements of the plunger 40, so as to deliver to the mold succeeding measured quantities of cork composition prior to each compacting stroke of the plunger 40.

The measuring valve in the form of the invention shown, consists of four vanes set 90° apart upon a shaft 58, said vanes moving in a casing 59 having an opening downwardly thereof and above an inclined chute 60 having an outlet opening at 61 above and in alignment with the open top of the cavity of the mold 35. Intermediate the outlet 61 and the measuring valve 57, is a reciprocatory gate 62 slidably mounted in relation to said chute and the hopper 56, and adapted to engage the bottom of the chute 60. This gate is adapted to be actuated by the extension 39 of the slide 20 by means of lugs 63 projecting from the upper end of said gate in the path of movement of said extension. The gate slides in slideways 64 formed upon the hopper 56.

25 The valve gate 57 is actuated by means of sprocket wheels 65 and 66 carried by the shaft 28 and idly mounted upon the shaft 58 respectively, and the connecting sprocket chain 67. While the sprocket wheels 65 and 66 rotate alternately in opposite directions in accord with the reciprocatory movement of the slide 20, the measuring valve 57 has only unidirectional movement imparted thereto by a mechanism actuated by the wheel 66 and operative upon the shaft 58. This mechanism in addition to imparting a timely actuation to the measuring device 57, is also so constructed that the operative connection between the shaft 58 and the sprocket wheel 66 will be automatically made inoperative to actuate the valve 57 to deliver cork composition to the chute 60 upon next to the last oscillation of the slide 20 of each cycle of operations of the machine, and during this stroke only, so that during the last stroke of each cycle, no cork will be fed to the mold as a result of the actuation of the gate 62, and this stroke may be utilized for forcing a closure plug 50 upon the already compacted mass of cork composition within the mold by the plunger 40. During this last stroke of the plunger, however, the measuring valve is operative to deliver a charge of cork composition to the chute 60 to be used as the initial charge in the mold to be filled during the succeeding cycle of operations of the machine, the movement of the shaft 58 during this last stroke of the plunger 40 and the slide 20 also serving to automatically position the closure plug in relation to the mold in the path of movement of the plunger.

65 The operative connections between the sprocket wheel 66 and the shaft 58, in the form of the invention shown, consists of a

hub 69, keyed to the shaft 58 and rotatable therewith. This hub has diametrically opposite ratchet teeth 70 and 71, adapted to be engaged by a pawl 72, pivoted adjacent the shaft 58, and adapted by engagement 70 with the teeth 70 or 71, to prevent a return movement of the shaft 58 with the return rotary movement of the sprocket wheel 66. Mounted in bearings parallel to the shaft 58, are diametrically oppositely disposed 75 ratchet pins 73 and 74 which are normally thrust toward the sprocket wheel 66 by springs 75 and 76, acting between a shoulder on said hub and collars 77 and 78 carried by said pins respectively.

The ends of the pins 73 and 74 adjacent the sprocket wheel 66 are rounded as shown, and are adapted to co-operate with cam shaped clutch teeth 79 and 80 formed upon the wheel 66. The faces of said teeth 79—80 are so positioned as to impart movement to the hub 69 with that movement of the sprocket wheel 66 coincident with the downward movement of the slide 20, and the cam shaped portion of said teeth are so formed as to move said pins outwardly against the tension of the springs 75 and 76, during the movement of said sprocket wheel 66 coincident with the upward movement of said slide 20. Hence, with the rotary movement 90 of the sprocket wheel 66 in one direction, the shaft 58 and the measuring valve 57 will be actuated to deliver a charge of cork composition from the hopper 56 to the chute 60, while upon the return oscillation of said sprocket wheel movement of the shaft 58 will be prevented by the engagement of the pawl 72 with one of the teeth 70 or 71 carried by the hub 69. Diametrically opposite ratchet pins 73 and 74 are used, because the operative movement of the shaft 58 is 180° in arc, and the clutch teeth 79 and 80 are therefore required to co-operate with the pins 73 and 74 successively.

100 By the use of ratchet pins movable in the manner described, it is apparent that actuation of the measuring valve 57 may be prevented during any down stroke of the slide 20 and plunger 40 by maintaining such ratchet pins 73 and 74 out of engaging relation with the clutch teeth 79 and 80 when they have been forced outwardly by the cam surfaces upon said clutch teeth. To secure this result, I idly mount upon the shaft 58, a ratchet wheel 81 having therein two segmental slots 82 and 83 having in the length thereof respectively, enlarged portions 84 and 85 adapted to receive enlarged heads 86 and 87 upon the ratchet pins 73 and 74 respectively.

115 Acting upon the ratchet wheel 81 is a spring 88 having a normal tendency to impart a movement to said ratchet wheel counter to its movement with the shaft 58. The hub 69 is provided with a stop pin 89 120

adapted to enter a recess 90 in the slot 82 so as to limit the movement of the wheel 81 under the control of said spring 88.

The ratchet wheel 81 is provided with four teeth 81^a, 81^b, 81^c and 81^d, as shown more particularly in Figs. 9 and 10 of the drawings, these teeth being set 90° apart. Two of these teeth, 81^a—81^c, positioned diametrically opposite each other, are adapted to be engaged by the pawl 91 when the wheel 81 has been so actuated as to prevent the co-operating engagement of the clutch teeth 79 and 80 with the ratchet pins 73 and 74, while the intermediate teeth 81^b—81^d, also set 180° apart, are adapted to be engaged by a thrust pawl 92 actuated by other mechanisms of the machine for the purpose of imparting movement of the wheel 81 with relation to the hub 69 when it is desired to prevent actuation of the measuring valve 57 during one reciprocatory movement of the slide 20 and its plunger 40.

The thrust pawl 92 is pivotally mounted upon a lever 93, and is provided with an adjusting screw 94, serving the two-fold function of accurately positioning this pawl with relation to the teeth 81^b and 81^d, and acting as a releasing means for the pawl 91 prior to the last stroke of the slide 20 and the plunger 40. The lever 93 is acted upon by a slotted link 95 pivoted to one arm 96 of a lever, the other arm 97 of which is acted upon by a lift rod 98 carrying a tappet 99, projected in the path of movement of the plunger 40 so that the actuation of the lever 93 and pawl 92 will be timed with relation to the position of the plunger as determined by the operative relations between same and the slide 20. The link 95 is provided with a set screw 100 acting upon the lever 93 so as to secure the desired quantity of movement of said lever. The lift rod 98 carries a fork 101, the branches of which straddle the arm 97.

The tappet 99 is so set on the rod 98 that this rod will receive a short movement as the plunger 40 ascends prior to its last compacting stroke, this movement being sufficient to cause the actuation of the means for preventing the feeding of cork during the up-stroke of the plunger 40 and slide 20 following the final compacting stroke. This positioning of the tappet will, upon the upward stroke of the plunger 40 prior to the final down stroke in its cycle of operations in packing one mold, impart a long movement to the rod 98, which will cause the push pawl 92 to release the pawl 91 and permit the controlling mechanism for the measuring valve to operate during the down stroke of the plunger so as to deliver a charge to the chute 60 prior to the initial stroke of the slide 20 and plunger 40 upon the next cycle of operations when the next mold is to be filled and packed. In other words, the pawl 92

receives two impulses upon succeeding up strokes of the plunger 40, the operative effect of which impulses will be determined by the position of the plunger with relation to the slide 20, the first of these impulses serving to make the feed mechanism inoperative, and the second impulse serving to restore this feed mechanism to its normal operative position.

The lower end of the rod 98 co-operates with an oscillatory latch member 102 acted upon by a spring 103. This member has therein a recess 104 adapted to receive the end of the rod, this recess being of a depth to prevent the complete withdrawal of the rod therefrom during the first, or short impulse thereof above referred to, while permitting its complete withdrawal during the second, or long impulse.

The rod 98 also carries a lug 105 adapted to engage a stop shoulder 106 to limit the downward movement of said rod independently of the latch member 102.

Carried by the guide 33 is an angle bar 107, having a slot 108 through the horizontal angle thereof, corresponding in dimensions with the open top of the mold. Rearwardly of this slot is positioned the plate forming the rear wall of the funnel-like outlet 61 for the chute 60, which plate also serves as a stop for properly positioning the closure plug for the mold. The horizontal flange of the angle 107 projects forwardly of this slot so as to serve as a support for this plug, while the successive charges of cork composition are delivered to and compacted within the mold. The lower edge of the chute 60 terminates above this angle, a distance slightly greater than the height of the plug, so as to afford the proper clearance for moving the plug above the opening 108, preparatory to the insertion of the plug within the mold.

The lower end of the chute 60 is provided with a stiffening bar 109, and the upper end of the rear plate of the outlet opening 61 is also provided with a brace 110, so as to prevent the yielding of this plate when the plug is moved into position to be forced into the mold. The plug itself is shown at 111, this plug having therethrough openings 112, adapted to register with openings 113 in the mold 35, so that when the plug is properly inserted within the mold, it may be locked in this position by means of bolts, thus preventing its displacement during the interval while the mold is in the baker or vulcanizer.

The plug 111 is adapted to be automatically moved into position above the opening 108, and the open top of the mold, during the final downward stroke of the plunger 40 and slide 20, of each cycle of operations of the machine, by means of a mechanism which I will now describe.

Mounted upon the frame of the machine 130

below the shaft 58, is a rock lever, one arm 114 of which extends to adjacent said shaft, and the other arm 115 of which extends downwardly adjacent the level of the horizontal flange of the angle bar 107. Pivotally connected to the arm 115 is a thrust bar 116 carrying a head 117, adapted to engage the plug 111. This head 117 is provided on its under side with a cam 118, spaced rearwardly of the end thereof which engages the bar 107, the portion of this head forwardly of said cam, in the direction of operative movement of the thrust member 116, being adapted to rest upon the horizontal flange 15 of the angle bar 107. Slidably mounted upon said bar 116 is a latch member 119 having a downturned end adapted to enter a socket 120 in the top of the plug 111. The latch member 119 is provided with elongated slots 20 121, adapted to receive a pin 122 carried by the rod 116. The end of said latch member is adapted to bear against the reinforcing bar 109, so as to accurately position the plug 111 in relation to the opening 108, while the 25 mold is being filled.

The pin and slot construction 121 and 122, permits movement of the rod 116, independently of the latch member, while the plug is receiving movement, but insures the proper 30 relative position of these parts at all other times. The latch member is acted upon by a spring 123 which will also serve to maintain the lever 114 and 115 in the proper operative relation to the mechanism for actuating the rod 116 through said lever, when 35 the plug is in position.

A plurality of such levers, 114 and 115, are used in the form of the invention shown, 40 two rods 116 and parts appurtenant thereto, being used, one, adjacent each end of the plug 111. If desired, however, the number of such thrust bars 116 may be increased, or the thrust bar may be so arranged as to secure the desired parallel movement of the 45 plug 111. Variation in the positioning or grouping of said members 116, may be resorted to, if desired.

Carried by the shaft 58 is a fitting having 50 oppositely disposed hooked members 124 adapted to co-operate with which is a dog 125 pivotally mounted upon the lever arm 114. This dog is provided with a heel 126 acted upon by a spring 127 normally lifting this dog out of the path of movement of the 55 members 124. Mounted above the shaft 58 is a lever 128, one arm of which carries an adjustable impact member 129, and the other arm of which is positioned in the path of movement of a striker 130 on a lift arm 60 131, said striker being positioned in the path of movement of the plunger 40 and so set upon said rod 131 that it will be engaged by said plunger during its upward movement prior to the final downward stroke of the plunger and of the slide 20. Hence

upon this downward stroke of the plunger and the slide, the dog 125 will be in the path of movement of one of the hooked members 124 as a result of the actuation of the lever 128 and the resulting engagement of the impact member 129 with said dog. 70

While the lift rod 98 will receive two impulses during each cycle of operations of the machine, the lift rod 131 need receive but one such impulse, which will, however, be 75 coincident with the long stroke of the lift rod 98.

The lever 114—115 is carried by a rock shaft 132 extending the full length of the machine so that duplication of this mechanism is not required. 80

Adjacent the lower end of the rod 131 is a latch member 133 acted upon by a spring 134 and having a recess 135 therein adapted to receive the lower end of this rod. The downward movement of the lift rod 131 is limited by a lug 136 co-operating with a stop 137 upon the frame of the machine. 85

The mechanism immediately above described is automatically set, upon the upward stroke of the plunger 40 following its final compacting stroke, and is actuated during the final downward stroke of the slide 20 and plunger 40. 90

The latch members 102 and 133 are carried respectively by rock shafts 138—139. Carried by said shafts respectively are centering members 140—141 having wedge-like surfaces adapted to enter corresponding openings 142—143 in the ends of the plug 100 111. These centering devices with the movement of the latch members 102 and 133 under the control of their respective springs 103 and 135, when the lift rods 98 and 131 are disengaged from said latch members, 105 will move inwardly and engage the plunger and center it accurately with relation to the mold cavity prior to the movement of the plug under the control of the mechanisms carried by the levers 114 and 115. The 110 wedge-like contacting surfaces between these members and the plug will result in the restoration of the latch members and the lift rods to their normal position after the plug has been properly inserted in the mold. 115

In conjunction with the plunger actuating mechanism, including the mechanism by which the effective compacting stroke of the plunger will be progressively decreased by the successive changes in the relation of the plunger to the mechanism which actuates same, to accommodate it to the increasing volume of cork composition accumulated within the mold, the mechanism by which succeeding measured charges of cork composition are delivered to the mold is required, including the means by which this mechanism is made inoperative when it is not desired to deliver cork to the mold, and the mechanism by which the closure plug is 120 125 130

inserted in the mold. I preferably provide an automatic stop mechanism by means of which the actuation of the slide 20 is interrupted substantially simultaneously with the proper positioning of the plug in the mold, so as to permit bolts to be inserted through the plug and the mold by hand, to lock this plug in a fixed relation to the mold, and, at the same time, to cause that interval between 10 succeeding cycles of the machine, required for the purpose of removing one completely packed and plugged mold, and substituting an empty mold therefor. This stop mechanism is so constructed that while it is 15 adapted to be set through the medium of the plunger 40, as determined by the position of said plunger relative to the slide 20, or as determined by the length of the plunger, the actuation of this mechanism 20 will occur only when the plunger is in its lowermost position.

In detail as shown in the accompanying drawings, this mechanism comprises a shift bar 144 operative upon the clutch 32. 25 Slidably mounted upon said bar is a clutch member 145, adapted to enter a recess 146 in said bar having a clutch shoulder thereon, adapted to co-operate with the clutch member 145. Said clutch member is adapted to 30 have vertical movement in relation to said bar, to permit it to enter and leave said recess.

Acting upon said member is a spring 147, having a normal tendency to so position it 35 that it will enter said recess 146. At 148 is a rock shaft having thereon a latch member 149, and an impact member 150, said impact member being connected with the clutch member 145 by a chain or other flexible 40 connection 151, passing about a pulley 152. Adjacent the latch member 149 is a lift rod 153, having an arm 165 engaging the tappet 99, and has secured thereto a block 154, which also carries a lock pin 155, 45 adapted to co-operate with the latch member 149. Acting upon the block 154 is a spring 156 acting to normally force said block and the lock pin carried thereby, towards the stop 157, in a manner to engage 50 the pin 155 with the latch member 149.

Carried by the crank wheel 23 are a sequence of tappets 158 and 158^a, the former of which is adapted by co-operation with the impact member 150, to actuate the shift bar 55 144 to stop the machine when the plunger 40 is at the limit of its downward movement upon the last stroke of a cycle of operations of the machine so as to cause said plunger to hold the closure plug firmly in 60 position while the stay bolts are being positioned with relation to said plug, and the adjacent walls of the mold, and the latter of which, is so positioned that upon the re-starting of the machine, prior to the removal of the mold, the upward movement of

the plunger will be limited to an extent to prevent the actuation of the gate 62 by the slide 20 until after the new mold has been positioned in the machine.

In conjunction with the mechanism just described, I provide a safety mechanism 70 consisting of a rock lever 159, one arm of which is adapted to enter a recess 160 in the shift bar 144, and the other arm of which is adapted to be engaged by the lift rod 153, 75 a construction which will automatically act to prevent an accidental movement of the shift bar 144 when the clutch 32 is released.

Acting upon the block 154 is a foot controlled lever 161, by means of which the lift 80 rod 153 and the lever 159 may be manually actuated independently of other mechanisms in the machine.

I also provide a hand lever 162 pivotally connected with the shift bar 144 to permit 85 the manual actuation of this bar in starting the machine, and foot controlled lever 163, for controlling the clutch member 145, or disengaging it from its co-operating recess 90 146, when it is desired to start the machine. 90

The band brake mechanism shown at 164 is a retard device acting upon the gear train 30 for the purpose of preventing overrunning of the machine when the clutch 32 is released. 95

In describing the operation of the machine, I will refer to the pawl 45 as a push pawl and the pawl 48 as a lift pawl, it being noted that the latch member 51 for holding this lift pawl out of engagement with the ratchet rack 44 is provided with a heel 51^a adapted to engage the head 54 of the adjacent guide rod 41, when the slide 20 is in the uppermost engaging position therewith and the plunger head 40 is in the lowermost position so as to permit said pawl to engage the uppermost ratchet tooth of the sequence 44 prior to the first down stroke of the plunger in each cycle of operations of the machine. 100 105 110

It is also to be noted that while I have herein referred to the progressive decrease of the effective stroke of the plunger 40, it is not to be understood that the actual stroke of the plunger varies since this movement is always with and in accordance with the movement of the slide 20. The effectiveness of the stroke of the plunger results from the progressive changing relation of the plunger with relation to said slide, so that with a given quantity of movement of the plunger, and of the slide upon succeeding strokes thereof, the effect secured is that of a progressively decreasing length of stroke. In other words, the actual result is the progressive shortening of the plunger mechanism, which has the same effect as a variance in the length of stroke, or as heretofore expressed in the specification, a variance in the effective stroke of the plunger. 115 120 125 130

The operation of the herein described machine is substantially as follows:—

In describing the operation of the machine, reference will be had to the position of parts as shown in Figs. 1, 3, 4 and 5, as these views show the conditions just prior to the initial compaction stroke of the plunger 40 and the slide 20, a charge of cork composition having already been delivered to the mold 35. The operation of the machine and the steps of this operation prior to the parts being brought into this relation will be described following the description of the functioning of the machine immediately after the final stroke of the plunger in the first cycle of operations, and in relation to the succeeding cycle of operations.

When the parts assume the position shown in the figures above referred to, the crank wheel 23 is already in motion, and as a result of its continued rotation, the slide 20 is drawn downwardly, the lift pawl 48 remaining in engagement with the uppermost tooth of the sequence of teeth or rack 44 and the push pawl 45 remaining out of engagement with the uppermost tooth of its sequence of teeth or rack 43 until the plunger head 40 enters the mold and encounters resistance therein either by engagement with the walls of the mold cavity or with the charge of cork composition therein. When the plunger thus meets resistance to its descent, the slide 20 will move toward the plunger head 40 along the stems 41 until the push pawl 45 engages the first tooth of its sequence of teeth or rack 43 and the lift pawl 48 passes from engagement with the first tooth of its sequence of teeth or rack 44 and engages the next lower tooth thereon. During this movement, the lost motion between the push pawl 45 and its pivot is taken up after the engagement of the pawl 45 with the tooth with which it co-operates at the moment. The result will be that toward the very end of the stroke when the crank wheel 23 is developing its greatest power, or when the crank of said wheel is approaching the bottom vertical center of the wheel, a positive pressure will be applied to the cork composition, which will cause it to receive the desired degree of compaction to ensure substantially uniform density throughout the entire charge upon which the plunger acts.

During the downward movement of the slide 20, the counterweights 25 will be raised through the medium of the chains 26 passing over the sprocket wheels 27, thus turning the shaft 28 which through the chain and sprocket mechanism 65, 66 and 67, will actuate the measuring valve 57 with a movement of 180° , thus delivering upon the chute 60, the cork composition to be used for the next charge, along which chute

it will descend in a manner to cause its substantially equal distribution throughout the entire width of the chute by the time it reaches and is accumulated at the gate 62.

During each cycle of operations the crank wheel 23 rotates continuously so that when the plunger 40 has reached the limit of its downward movement, the direction of movement of the slide 20 is reversed, this slide in its ascent carrying with it the plunger 40 as a result of the engagement of the lift pawls 48 with their respective racks 44.

During the ascent of the slide 20, the counterweights 25 will descend, imparting a reverse rotary movement to the sprocket wheels 27, shaft 28 and the chain and sprocket mechanism 65, 66 and 67, the shaft 58, however, being held against rotation by the pawl 72 engaging one of the teeth 70—71 upon the hub 69. A detailed description of the operation of this feed mechanism will be given hereinafter, the foregoing merely being to show the relative timing of the different mechanisms.

As the slide 20 approaches the limit of its upward movement, it will engage the various lugs 63 and thus raise the gate 62 so as to permit the cork retained upon the chute 60 thereby to flow into the mold. Also as the slide 20 approaches the limit of its upward movement, the stem 46 of each push pawl 45 will engage its plate 52, thus oscillating the push pawl 45 and disengaging it from the tooth with which it was in operative relation upon the conclusion of the preceding descent of the slide 20, the lost motion connection between this pawl 45 and its pivot permitting it to drop sufficiently to pass the tooth with which it was just engaged, and be in a position where it can engage the next lower tooth of the rack or sequence of teeth 43 upon the next descent of the plunger.

It is to be understood that each of the push pawls 45 and lift pawls 48 and their associated parts will operate in the same manner as that described, irrespective of the number of bars 42 which are employed in the machine.

The above described operations will be repeated until the push pawl 45 and the lift pawl 48 have successively engaged each ratchet tooth of the sequences 43 and 44 respectively, except the last tooth, cork being fed by the measuring valve 57 to upon the chute 60 during each downward movement of the plunger 40 and of the slide 20, excepting during the next to the last down stroke, the charge thus measured out being delivered to the mold upon the succeeding up stroke of said slide and said plunger.

Upon next to the last stroke of the slide 20 and plunger 40, or upon the sixteenth stroke, as shown in the accompanying drawings, no cork will be fed to the chute 60 so that upon

- the up stroke preceding the final down stroke, the movement of the gate 62 will not result in the feeding of any cork to the mold. Upon this up stroke, the pawls 45 and 48 will be in position with relation to the teeth upon the respective bars, and the plunger head 40 will be in position with relation to the slide 20, as shown in Fig. 7 of the drawings.
- As the plunger 40 and the slide 20 pass upwardly to the position shown in Fig. 7, one end of said plunger, by engagement with the tappet 99, will give the second impulse to the lift rod 98, with the three-fold result of positioning the parts of the controlling mechanism for the shaft 58 so that said shaft may be rotated during the final downward stroke of said plunger; positioning the stop mechanism so that it will be set upon completion of this stroke, and releasing the latch member 102; and the other end of said plunger will engage the tappet 130, and raise the lift rod 131 so as to actuate the lever 128, and position the dog 125 in the path of movement of one of the hooked members 124 and release the latch member 133.
- The simultaneous lifting of the rods 98 and 131 releasing the latch members 102 and 133, permits said latch members to rock under their springs 103 and 134, thus rocking the shafts 138 and 139, and bringing the centering heads 140 and 141 toward each other and in engaging relation with the plug 111. This accurately positions this plug with relation to the opening 108, and the open top of the mold, the wedge-shaped heads 140 and 141 being of a width to engage the plug 111 while it is resting upon the flange 107, and while it is being moved into position above the mold, said plug being held suspended above the opening 108 by these heads until it is actually forced to within the mold.
- As the plunger 40 and slide 20 descend for the final stroke of the cycle of operations, the shaft 58 will be rotated, causing cork composition to be fed by the measuring pawl 57 to upon the chute 60, and at the same time rotating the hooked member 124 in a manner to cause the oscillation of the levers 114 and 115, to cause the push rod 116 and the parts appurtenant thereto to force the plug 111 into a position in the path of movement of the plunger 40, so that this final stroke of said plunger will be utilized to position this plug within the mold. This positioning of the plug, in the event of any slight expansion of the final charge of compacted cork composition, exerts a compacting pressure, so that the entire mass of cork composition within the mold will be closely confined upon all sides thereof.
- As the plug 111 is forced to within the mold by the plunger 40, the co-operating wedge surfaces thereon and on the centering members 140—141 will cause a return rocking movement of these members so as to permit the lift bars 102 and 133 and the parts actuated thereby to return to their normal position preparatory to the succeeding cycle of operations of the machine.
- The detailed operation of the mechanism for positioning the plug 111 in proper relation to be forced to within the mold, will be described more fully hereinafter.
- As the plunger 40 reaches its lowermost position, the tappet 158 upon the crank wheel 23 will engage the impact member 150 to cause the stoppage of the machine in a manner to be hereinafter more fully described, while this plunger is still in its lowermost position. This stoppage of the machine will hold the plug 111 in a position where bolts may be inserted through the openings therein, and the registering openings in the sides of the mold.
- As the plunger approaches the limit of its final downward stroke, the slide 20 will have movement toward said plunger, to ensure the engagement of the push pawl 45, with the last tooth upon its sequence or rack 43, during which movement of the slide relative to the plunger head, the stem 49 will be engaged with the top of the plunger bar 40 at a time to cause continued movement of the slide 20 to raise this stem against the tension of the spring 50, and oscillate the lift pawl 48 so as to disengage it from the last tooth upon its sequence or rack 44, and bring the top of this pawl to a position where it will pass under the latch member 51. The lift pawl 48 will thus be in a position where, upon the next up stroke of the slide 20, it will be inoperative with relation to the bar 42, and thus permit a partial return movement of the slide 20, during its next up stroke, without imparting any movement to the plunger 40. As the slide 20, however, approaches the enlarged head 54 of the stems 41, the heel 51^a of the latch member will engage this enlarged head, thus lifting the latch member and permitting the lift pawl 48 to engage the first tooth of its sequence or rack 44, thus positioning the parts so that upon the continued up stroke of said slide 20, a corresponding up stroke will be imparted to the plunger 40.
- The stop mechanism is so constructed, that while the clutch 23 may be manually set to cause this up stroke of the slide 20, it will be automatically actuated to stop the machine before this slide engages the lugs 63 of the gate 62, thus positioning the various parts of the machine where the mold 35, which has been completely filled, packed and plugged, may be removed from its position in the machine, and an empty mold substituted therefor.
- In removing the mold, the clamps 37 are

released, and the links 38 swung downwardly to disengage these clamps from the clamp bars 36, these clamp bars then being swung away from the mold, so as to afford the desired clearance to permit the free movement of the mold. The empty mold is positioned between these clamp bars, and the guide bars 33. The clamp bars 36 are then raised in engaging relation with the forward face of said mold, and the links 38 swung downwardly, and the cams 37 actuated to force the clamp bars into a position which will ensure the desired vertical alinement of the mold cavity with the plunger head 40.

Adverting to the mechanism for actuating the measuring valve in a manner to secure the feeding of successive charges of cork composition to the mold, as described above, it has already been pointed out that upon each down stroke of the plunger 40 and slide 20, the sprocket wheel and chain mechanism 65, 66 and 67, causes a movement of 180° in the shaft 58 and in the measuring valve 57, to deliver a charge of cork composition upon the chute 60, upon which it will be held by the gate 62 until upon the next up stroke of the slide 20, this gate is opened so as to permit the cork composition to flow into the mold. It has also been pointed out that the final compacting stroke of the plunger is next to the last stroke of the cycle of operations in filling and compacting cork composition in a mold, and that upon the up stroke prior to this last compacting stroke, the actuating mechanism operative upon the shaft 58 is made inoperative with relation thereto, so that no cork composition will be delivered by the valve 57 during the final compacting stroke of the plunger so that upon the upstroke of the plunger 40 and slide 20 prior to the final stroke of the cycle of operations of the machine, no cork will be delivered to the mold, but this mechanism will again be made operative so that during the final stroke, cork composition will be delivered to the chute 60 preparatory to the first stroke of the succeeding cycle of operations.

I will now describe in detail the functions of the controlling mechanism for the measuring device, by which cork composition is delivered in succeeding measured quantities to the mold prior to each compacting stroke, but not prior to the final stroke, of the plunger, at which time no cork is required to be delivered, but it is required that a charge be accumulated so as to make the first stroke of the succeeding cycle of operations of the machine effective in filling the mold.

As the slide 20 is drawn downwardly by the crank shaft 23 and pitman 24, the chain 26 in addition to raising the counterweights, turns the shaft 28 in a direction which will, through the sprocket wheel 65 and chain 67,

rotate the sprocket wheel 66 and the cam-like clutch members 79 and 80 thereon, in a direction which will impart a feeding movement to the shaft 58 and the measuring valve 57. As the clutch members 79 and 80 are thus turned, they will engage the ratchet pins 73 and 74 and thus impart a 180° movement to the hub 69, carrying said ratchet pins. Upon the completion of this 180° movement, the pawl 72 engages one of the teeth 70 or 71, thus preventing a return movement of the hub.

Upon the following upward stroke of the slide 20 the direction of rotation of the sprocket wheel 66 is reversed, but the hub 69 and shaft 58 are held against movement therewith by said pawl 72. As the hub 69 is thus turned, the enlarged heads 86 and 87 of the ratchet pins 73 and 74 will be seated in the enlarged portions 84 and 85 of the ratchet wheel 81, so as to cause this ratchet wheel to have movement with the hub 69. While the sprocket wheel 66 has an oscillatory movement, the shaft 58 receives an intermittent unidirectional movement therefrom.

During the return movement of the sprocket wheel 66, the cam surfaces of the clutch members 79 and 80 will force the ratchet pins 73 and 74 outwardly, the length of these cam surfaces causing the clutch members 79 and 80 to respectively engage the pins 73 and 74 successively, since as these pins ride beyond the high point of said cams, they will drop into position in advance of the clutch members, so as to be in position to be engaged thereby upon the next actuation of said clutch members. During the operations of the shaft 58 for delivering cork composition to the chute 60, the pawl 92 is inoperative with relation to the ratchet wheel 81, although this pawl will be in a position where it can engage any of the teeth 81^a, 81^b, 81^c, or 81^d, the pivotal support of this pawl permitting said teeth to pass the pawl.

Upon the upstroke of the plunger 40 preceding its final compacting stroke, it will engage the tappet 99 and raise the lift rod 98, the pawl 101 oscillating said lever 96—97, sufficiently to draw the link 95 downwardly to impart an oscillatory movement to the lever 93, which will cause the thrust pawl 92 to act upon the tooth 81^b of the ratchet wheel 81, and impart a partial rotation to this wheel sufficient to cause the portions thereof adjacent the slots 82 and 83, to pass beneath the enlarged heads 86 and 87 of the ratchet pins 73 and 74. This prevents the return of said pins into operative relation with the clutch members 79 and 80, prior to the next movement of said members which ordinarily would impart rotary movement to the shaft 58. This movement of the ratchet wheel 81 is against the tension of 130

the spring 88, and brings the tooth 81^a of this wheel into a position where it will be engaged by the pawl 91, and prevent a return movement of the wheel under the control of said spring, thus causing the hub 69 to remain stationary during the next movement of the sprocket wheel 66, during the next to the last down movement, or final compacting stroke, of the plunger 40.

Upon the up stroke of the plunger 40, preceding its final down stroke of its cycle of operations, the lift rod 98 will receive a second and longer impulse owing to the changed position of the plunger 40 with relation to the slide 20, which longer impulse will cause the lever 93 to be again oscillated, but to a greater extent owing to the increased length of the impulse. This longer movement causes the adjustment screw 94 to engage the pawl 91, and disengage it from the tooth 81^b, permitting a return oscillatory movement of the wheel 81 under the control of the spring 88, this movement being limited by the stop pin 89 entering the recess 90. This return movement of the wheel 81 will permit the ratchet pins 73 and 74 to move into engaging position with relation to the thrust members 79 and 80 so that upon the next down stroke of the plunger, the shaft 58 will be turned in the manner heretofore described.

The adjustment screw 94 has the two-fold function of permitting accuracy in the positioning of the thrust pawl 92, in relation to the teeth 81^b and 81^c, and of disengaging the holding pawl 91 from the teeth 81^a or 81^b in the manner described.

The set screw 100 may be used for insuring a desired relation of the adjusting screw 94 and the stop pawl 91, the said screws 94 and 100 giving a range of adjustment which will secure the desired relation of parts with regard to the movements of the lift rod 98.

As the lift rod 131 is raised upon the up stroke of the plunger 40, preceding the final down stroke of this plunger in a cycle of operations of the machine, causing the release of the latch member 133 and the oscillation of the lever 128 as heretofore described, the movement of the shaft 58 upon the final plunger stroke will cause one of the hooked members 124 to engage the dog 125 and rock the lever 114-115, or all of such levers carried by the rock shaft 132, thus moving the thrust bar 116 and its head 117 toward and into engagement with the plug 111. This movement is against the tension of the spring 123, and said thrust bar has movement in the latch member 119. As the head 117 moves forwardly, the cam 118 thereon, by engagement with the horizontal flange 107, will raise both the bar and the latch member 119 so that said latch member is disengaged from the plug 111 and per-

mits the continued movement of the thrust bar 116 to impart the desired movement to the plug 111.

The arrangement of the fitting carrying the hooked members 124 is such that the operation above described will occur during the early part of the downward stroke of the plunger, so that when the plunger approaches the end of its stroke where it can engage the plug 111, this plug will already be in a position where it can be forced into the mold by the plunger.

As the plug is moved towards the mold the centering members 140-141 are oscillated to cause a return movement of the latch members 102 and 133, thus permitting the lift rods 98 and 131 to descend to their normal position, which will permit the spring 127 to raise the dog 125 out of the path of the succeeding hooked member 124 and maintain the lever 128 in its engaging relation to the tappet 130.

Adverting now to the stop mechanism, as the lift rod 98 is raised upon next to the last up stroke of the plunger, while it will impart movement to the lift bar 153 by means of the arm 165 thereon engaging the tappet 99, this movement will have no operative effect in stopping the machine. Upon the upward movement preceding the final down stroke of the plunger 40, however, the greater movement during the second impulse of the lift rod 98 will raise the lift bar 153 and with it the block 154 to an extent to disengage the lock pin 155 carried thereby from the recess in the latch member 149, and at the same time afford clearance which will permit the rock lever 159 to move from its engaging relation with the recess 160 in the shift bar 144. When the parts are in this position, the rock shaft 148 carrying the latch member 149 and the impact member 150, will be rotated as a result of the movement of the clutch member 145 under the control of the spring 147. When the parts are so set, the impact member 150 will be in the path of movement of the tappet 158 which will be approximately 180° removed from the position of said impact member.

When the parts are in this position, a return movement of the lift bar will have no operative effect in changing the setting of the stop mechanism. As the clutch member 145 is moved in the manner described by the spring 147, it will drop into the recess 146 in the shift bar 144, the lever 163 oscillating under the weight of this clutch member to permit this engagement between the clutch member and the shift bar.

Upon the completion of the next 180° of movement of the crank wheel 23, the tappet 158 thereon will engage the impact member 150, and oscillate same in a manner to impart longitudinal movement to the clutch member 145 and therethrough to the shift 130

bar 144 sufficient to release the clutch 32. This will instantly stop the machine, the band brake 164 assisting in a quick stoppage. As the shift bar 144 is thus moved, 5 the lever 159 will engage the shouldered recess 160, and thus prevent an accidental return movement of the shift bar. When the machine thus stops, the plunger 40 will be in engagement with the plug 111 and will 10 hold this plug in this position with the openings therethrough in register with the openings in the side walls of the mold so as to permit bolts to be inserted therethrough in the manner heretofore described. 15 When it is desired to remove the mold, the foot lever 161 is used to raise the block 154, and with it the lock pin 155 and the lift rod 153, this movement releasing the safety mechanism including the rock lever 20 159 and permitting the impact member 150 to be drawn by the spring 147 and the clutch member 145 in the path of movement of the tappet 158, which is set less than 180° from said impact member. The foot lever 163 is 25 then actuated to disengage the clutch member 145 from the recess 146 in the shaft bar, thus permitting the hand lever 162 to be used to draw the bar 144 forwardly to reset the clutch. As the clutch is reset, the crank 30 wheel 23 will be actuated to raise the slide 20 and plunger 40, but before said slide member engages the lugs 63 of the gate 62, the tappet 158 will actuate the impact member 150 to again stop the machine in the 35 manner heretofore described. When a new mold is in position, the safety mechanism is again released, and the foot lever 163 and the hand lever 162 used to manually set the clutch for causing the succeeding cycle of 40 operations of the machine.

With the continued up stroke preparatory to the initial compacting stroke of the plunger, the gate 62 will be raised, thus permitting the charge of cork composition fed 45 upon the chute 60, as a result of the actuation of the measuring valve 57 during the last down stroke of the plunger, to enter the mold as the first charge therein.

It will be understood that as the tappets 50 158 or 158^a actuate the impact member 150 and the rock shaft 159 carrying same and the latch member 149, the lock pin 155 will enter the recess in said latch member and hold the impact member 150 out of the path 55 of movement of said tappets 157 and 158.

The arrangement of the lift rods ensures accuracy in the timing of the making of the cork composition delivery mechanism inoperative, of the positioning of the closure plug, and of the stoppage of the machine, with relation to each other and in relation to the operative effect of the plunger in packing the cork composition within the mold, and makes all of these mechanisms operative at an interval determined by the

position of the plunger 40 with relation to the slide 20.

It is not my intention to limit the invention to the precise details of construction shown in the accompanying drawings. 70 While I have found the push and lift pawls to be highly efficient in use in securing the desired progressive changing of the relation of the plunger 40 to the slide 20 to effect a progressive shortening in the length of the 75 plunger, or a decrease in the length of its effective stroke, it is apparent that other means may be employed for securing the same relative change in the position of these parts, without departing from the spirit 80 and scope of the invention. Furthermore, the detailed construction and arrangement of the various mechanisms and parts may be varied while still securing the same operative effects and the same sequence of operations as are herein described. 85

Having described the invention, what I claim as new and desire to have protected by Letters Patent, is:—

1. A cork slab packing machine embodying therein a support for a mold, a plunger adapted to enter said mold, a reciprocatory slide, means whereby said slide receives uniform reciprocatory movement, means carried by said slide and adapted to operatively engage said plunger and to impart positive reciprocatory motion thereto, means whereby the operative relation between said last named means and said plunger will be automatically varied with each stroke of said slide and said plunger, to cause a progressive decrease in the effective length of succeeding strokes of said plunger to compensate for the increasing volume of cork composition in said mold, and means delivering a measured quantity of cork composition to within said mold prior to each stroke of the plunger inwardly of the mold. 100

2. A cork slab packing machine embodying therein a support for a mold, a plunger adapted to enter said mold, a reciprocatory slide, means whereby said slide receives uniform reciprocatory movement, means carried by said slide and adapted to operatively engage said plunger and to impart positive reciprocatory motion thereto, means whereby the operative relation between said last named means and said plunger will be automatically varied with each stroke of said slide and said plunger, to cause a progressive decrease in the effective length of succeeding strokes of said plunger to compensate for the increasing volume of cork composition in said mold, means delivering a measured quantity of cork composition to within said mold prior to each stroke of the plunger inwardly of the mold, and automatically acting means for stopping the machine after a predetermined number of strokes of said plunger. 110 115 120 125 130

3. A cork slab packing machine embodying therein a support for a mold, a plunger adapted to enter said mold, a reciprocatory slide, means whereby said slide receives uniform reciprocatory movement, means carried by said slide and adapted to operatively engage said plunger and to impart positive reciprocatory motion thereto, means whereby the operative relation between said last named means and said plunger will be automatically varied with each stroke of said slide and said plunger, to cause a progressive decrease in the effective length of succeeding strokes of said plunger to compensate for the increasing volume of cork composition in said mold, means delivering a measured quantity of cork composition to within said mold prior to each stroke of the plunger inwardly of the mold, and means for positioning a closure plug above the open top of a mold and within the path of movement of said plunger whereby the last of a predetermined number of strokes of said plunger will force said plug in a mold.

4. A cork slab packing machine embodying therein a support for a mold, a plunger adapted to enter said mold, a reciprocatory slide, means whereby said slide receives uniform reciprocatory movement, means carried by said slide and adapted to operatively engage said plunger and to impart positive reciprocatory motion thereto, means whereby the operative relation between said last named means and said plunger will be automatically varied with each stroke of said slide and said plunger, to cause a progressive decrease in the effective length of succeeding strokes of said plunger to compensate for the increasing volume of cork composition in said mold, means delivering a measured quantity of cork composition to within said mold prior to each stroke of the plunger inwardly of the mold, means making the means for delivering cork composition to within the mold inoperative to deliver cork composition to the mold upon the last stroke of said plunger, means for positioning a closure plug above the open top of a mold and within the path of movement of said plunger whereby the last of a predetermined number of strokes of said plunger will force said plug in a mold.

5. A cork slab packing machine embodying therein a support for a mold, a plunger adapted to enter said mold, a reciprocatory slide, means whereby said slide receives uniform reciprocatory movement, means carried by said slide and adapted to operatively engage said plunger and to impart positive reciprocatory motion thereto, means whereby the operative relation between said last named means and said plunger will be automatically varied with each stroke of

said slide and said plunger, to cause a progressive decrease in the effective length of succeeding strokes of said plunger to compensate for the increasing volume of cork composition in said mold, means delivering a measured quantity of cork composition to within said mold prior to each stroke of the plunger inwardly of the mold, means for positioning a closure plug above the open top of a mold and within the path of movement of said plunger whereby the last of a predetermined number of strokes of said plunger will force said plug in a mold, and automatically acting means for stopping the machine after a predetermined number of strokes of said plunger.

6. A cork slab packing machine embodying therein a support for a mold, a plunger adapted to enter said mold, a reciprocatory slide, means whereby said slide receives uniform reciprocatory movement, means carried by said slide and adapted to operatively engage said plunger and to impart positive reciprocatory motion thereto, means whereby the operative relation between said last named means and said plunger will be automatically varied with each stroke of said slide and said plunger, to cause a progressive decrease in the effective length of succeeding strokes of said plunger to compensate for the increasing volume of cork composition in said mold, means delivering a measured quantity of cork composition to within said mold prior to each stroke of the plunger inwardly of the mold, means making the means for delivering cork composition to within the mold inoperative to deliver cork composition to the mold upon the last stroke of said plunger, means for positioning a closure plug above the open top of a mold and within the path of movement of said plunger whereby the last of a predetermined number of strokes of said plunger will force said plug in a mold, and automatically acting means for stopping the machine after a predetermined number of strokes of said plunger.

7. A cork slab packing machine embodying therein a support for a mold, a plunger adapted to enter said mold, a reciprocatory slide, means whereby said slide receives uniform reciprocatory movement, co-acting means carried by said slide and said plunger whereby positive pressure will be applied by the slide to the plunger upon the down stroke of the slide for packing the cork composition, and for raising the plunger upon the up stroke of the slide, fixed means operative upon said coacting means between succeeding down strokes of the plunger, whereby said co-acting means between the plunger and the slide will be so set as to cause the progressive shortening of the plunger upon succeeding strokes thereof, and means delivering a measured quantity

of cork composition to within said mold prior to each stroke of the plunger inwardly of the mold.

8. A cork slab packing machine embodying therein a support for a mold, a plunger adapted to enter said mold, a reciprocatory slide, means whereby said slide receives uniform reciprocatory movement, co-acting means carried by said slide and said plunger whereby positive pressure will be applied by the slide to the plunger upon the down stroke of the slide for packing the cork composition, and for raising the plunger upon the up stroke of the slide, fixed means operative upon said co-acting means between succeeding down strokes of the plunger, whereby said co-acting means between the plunger and the slide will be so set as to cause the progressive shortening of the plunger upon succeeding strokes thereof, means delivering a measured quantity of cork composition to within said mold prior to each stroke of the plunger inwardly of the mold, and means whereby the co-acting means between said plunger and said slide to raise the plunger will be made inoperative after a predetermined number of downward strokes of the plunger, and will be made operative during the following up stroke of said slide.

9. A cork slab packing machine embodying therein a support for a mold, a plunger adapted to enter said mold, a reciprocatory slide, a bar carried by said plunger and slidably mounted in said slide, said bar having a sequence of upwardly presented ratchet teeth thereon, a pawl carried by said slide in operative relation with said ratchet teeth, means whereby said pawl will be disengaged from one ratchet tooth and be positioned to engage the adjacent tooth after each down stroke of the slide and the plunger, means carried by said slide and said plunger independent of said sequence of ratchet teeth and said pawl for raising the plunger with the slide upon each up stroke thereof, and means delivering a measured quantity of cork composition to within said mold prior to each stroke of the plunger inwardly of the mold.

10. A cork slab packing machine embodying therein a support for a mold, a plunger adapted to enter said mold, a reciprocatory slide, a bar carried by said plunger and slidably mounted in said slide, said bar having a sequence of upwardly presented ratchet teeth thereon, a pawl pivotally mounted upon said slide in operative relation with said ratchet teeth, said pawl having an enlarged bearing opening therein whereby it may move longitudinally of said sequence of ratchet teeth, a spring pressed stem carried by said pawl, an impact plate adjacent the top of the machine in the path of movement of said stem, whereby said pawl will

be disengaged from one ratchet tooth and be positioned to engage the adjacent tooth after each down stroke of the slide and the plunger, means carried by said slide and said plunger independent of said sequence of ratchet teeth and said pawl for raising the plunger with the slide upon each up stroke thereof, and means delivering a measured quantity of cork composition to within said mold prior to each stroke of the plunger inwardly of the mold.

11. A cork slab packing machine embodying therein a support for a mold, a plunger adapted to enter said mold, a reciprocatory slide, a bar carried by said plunger and slidably mounted in said slide, said bar having a sequence of upwardly presented ratchet teeth thereon, a pawl carried by said slide in operative relation with said ratchet teeth, means whereby said pawl will be disengaged from one ratchet tooth and be positioned to engage the adjacent tooth after each down stroke of the slide and the plunger, said bar having a sequence of downwardly presented ratchet teeth thereon, a pawl carried by said slide and co-operating with the teeth of said second sequence of ratchet teeth, whereby movement of said slide to cause said first named pawl to engage an adjacent tooth, will cause said last named pawl to engage the adjacent tooth of its sequence so that upon each up stroke of said slide, it will impart upward movement to said plunger, and means delivering a measured quantity of cork composition to within said mold prior to each stroke of the plunger inwardly of the mold.

12. A cork slab packing machine embodying therein a support for a mold, a plunger adapted to enter said mold, a reciprocatory slide, a bar carried by said plunger and slidably mounted in said slide, said bar having a sequence of upwardly presented ratchet teeth thereon, a pawl carried by said slide in operative relation with said ratchet teeth, means whereby said pawl will be disengaged from one ratchet tooth and be positioned to engage the adjacent tooth after each down stroke of the slide and the plunger, said bar having a sequence of downwardly presented ratchet teeth thereon, a pawl carried by said slide and co-operating with the teeth of said second sequence of ratchet teeth, whereby movement of said slide to cause said first named pawl to engage an adjacent tooth, will cause said last named pawl to engage the adjacent tooth of its sequence so that upon each up stroke of said slide, it will impart upward movement to said plunger, means whereby said last named pawl will be moved and maintained out of the operative relation to said sequence of ratchet teeth after a predetermined number of downward strokes of said plunger and said slide, and will be made operative dur-

ing the following upward stroke of said slide, and means delivering a measured quantity of cork composition to within said mold prior to each stroke of the plunger inwardly of the mold.

13. A cork slab packing machine embodying therein a support for a mold, a plunger adapted to enter said mold, a reciprocatory slide, a bar carried by said plunger and slidably mounted in said slide, said bar having a sequence of upwardly presented ratchet teeth thereon, a pawl pivotally mounted upon said slide in operative relation with said ratchet teeth, said pawl having an enlarged bearing opening therein whereby it may move longitudinally of said sequence of ratchet teeth, a spring pressed stem carried by said pawl, an impact plate adjacent the top of the machine in the path of movement of said stem, whereby said pawl will be disengaged from one ratchet tooth and be positioned to engage the adjacent tooth after each down stroke of the slide and the plunger, said bar having a sequence of downwardly presented ratchet teeth thereon, a pawl carried by said slide and co-operating with the teeth of said second sequence of ratchet teeth, whereby movement of said slide to cause said first named pawl to engage an adjacent tooth, will cause said last named pawl to engage the adjacent tooth of its sequence so that upon each up stroke of said slide, it will impart upward movement to said plunger, means whereby said last named pawl will be moved and maintained out of the operative relation to said sequence of ratchet teeth after a predetermined number of downward strokes of said plunger and said slide, and will be made operative during the following upward stroke of said slide, and means delivering a measured quantity of cork composition to within said mold prior to each stroke of the plunger inwardly of the mold.

14. A cork slab packing machine embodying therein a support for a mold, a plunger adapted to enter said mold, a reciprocatory slide, a bar carried by said plunger and slidably mounted in said slide, said bar having a sequence of upwardly presented ratchet teeth thereon, a pawl carried by said slide in operative relation with said ratchet teeth, means whereby said pawl will be disengaged from one ratchet tooth and be positioned to engage the adjacent tooth after each down stroke of the slide and the plunger, said bar having a sequence of downwardly presented ratchet teeth thereon, a pawl carried by said slide and co-operating with the teeth of said second sequence of ratchet teeth, whereby movement of said slide to cause said first named pawl to engage an adjacent tooth, will cause said last named pawl to engage the adjacent tooth of its sequence so that upon each up stroke of

said slide, it will impart upward movement to said plunger, a spring pressed stem carried by said last named pawl in a position to engage the plunger after said plunger and said slide have reached a predetermined relative position, a latch member carried by said slide adapted to engage said pawl and hold it out of engaging relation with the teeth of the sequence with which it co-operates, means carried by said plunger adapted to release said latch as a result of upward movement of said slide, independently of the plunger, and means delivering a measured quantity of cork composition to within said mold prior to each stroke of the plunger inwardly of the mold.

15. A cork slab packing machine embodying therein a support for a mold, a plunger adapted to enter said mold, a reciprocatory slide, means whereby said slide receives uniform reciprocatory movement, means carried by said slide and adapted to operatively engage said plunger and to impart positive reciprocatory motion thereto, means whereby the operative relation between said last named means and said plunger will be automatically varied with each stroke of said slide and said plunger, to cause a progressive decrease in the effective length of succeeding strokes of said plunger to compensate for the increasing volume of cork composition in said mold, a hopper adapted to receive cork composition, a measuring valve, a chute extending from adjacent said valve to adjacent the open top of the mold, a gate co-operating with said chute, means actuated by the movement of said slide whereby said gate will be opened between succeeding down strokes of the plunger and slide, and means for intermittently actuating said valve.

16. A cork slab packing machine embodying therein a support for a mold, a plunger adapted to enter said mold, a reciprocatory slide, means whereby said slide receives uniform reciprocatory movement, means carried by said slide and adapted to operatively engage said plunger and to impart positive reciprocatory motion thereto, means whereby the operative relation between said last named means and said plunger will be automatically varied with each stroke of said slide and said plunger, to cause a progressive decrease in the effective length of succeeding strokes of said plunger to compensate for the increasing volume of cork composition in said mold, a hopper adapted to receive cork composition, a measuring valve, a chute extending from adjacent said valve to adjacent the open top of the mold, a gate co-operating with said chute, means actuated by the movement of said slide whereby said gate will be opened between succeeding down strokes of the plunger and slide, means for intermittently actuating said valve,

means whereby the means for actuating said valve will be made inoperative prior to the final down stroke of said slide and said plunger, and means whereby a plug is inserted in the path of movement of said plunger and in alinement with the open top of a mold so as to cause the final down stroke of said plunger to insert said plug in the mold.

17. A cork slab packing machine embodying therein a support for a mold, a plunger adapted to enter said mold, a reciprocatory slide, means whereby said slide receives uniform reciprocatory movement, means carried by said slide and adapted to operatively engage said plunger and to impart positive reciprocatory motion thereto, means whereby the operative relation between said last named means and said plunger will be automatically varied with each stroke of said slide and said plunger, to cause a progressive decrease in the effective length of succeeding strokes of said plunger to compensate for the increasing volume of cork composition in said mold, a hopper adapted to receive cork composition, a valve shaft, a rotary measuring valve carried thereby, a chute extending from adjacent the open top of a mold, a gate co-operating with said chute, a shaft, means whereby movement is imparted to said shaft alternately in opposite direction in accordance with the movements of said slide, and operative connection between said last named shaft and said valve shaft, including therein a member carried by and movable with said valve shaft, a member idly mounted upon said valve shaft, cam shaped clutch members carried by said last named member, ratchet pins carried by said first named member, a pawl operative upon said first named member whereby unidirectional, intermittent movement is imparted to said valve, means adapted to maintain said ratchet pins out of the operative relation to said clutch members, means actuated after a predetermined number of strokes of said slide whereby said last named means may be actuated to make said pins inoperative, and upon the succeeding stroke of said slide permit said ratchet pins to be restored to their operative position, and connections between said last named shaft and said member idly mounted on the valve shaft.

18. A cork slab packing machine embodying therein a support for a mold, a plunger adapted to enter said mold, a reciprocatory slide, means whereby said slide receives uniform reciprocatory movement, means carried by said slide and adapted to operatively engage said plunger and to impart positive reciprocatory motion thereto, means whereby the operative relation between said last named means and said plunger will be automatically varied with each stroke of said slide and said plunger, to cause a progressive decrease in the effective length of succeeding strokes of said plunger to compensate for the increasing volume of cork composition in said mold, a hopper adapted to receive cork composition, a valve shaft, a rotary measuring valve carried thereby, a chute extending from adjacent the open top of a mold, a gate co-operating with said last named member, cam shaped clutch members carried by said first named member, ratchet pins carried by said first named member but passing through, and having an enlarged head adapted to enter said enlarged portions of said slots, and to engage said wheel adjacent the other portions of said slots, a pawl operative upon said first named member whereby unidirectional, intermittent movement is imparted to said valve, means adapted to maintain said ratchet pins out of the operative relation to said clutch members, means actuated after a predetermined number of strokes of said slide whereby said last named means may be actuated to make said pins inoperative, and upon the succeeding stroke of said slide permit said ratchet pins to be restored to their operative position, and connections between said last named shaft and said member idly mounted on the valve shaft.

19. A cork slab packing machine embodying therein a support for a mold, a plunger adapted to enter said mold, a reciprocatory slide, means whereby said slide receives uniform reciprocatory movement, means carried by said slide and adapted to operatively engage said plunger and to impart positive reciprocatory motion thereto, means whereby the operative relation between said last named means and said plunger will be automatically varied with each stroke of said slide and said plunger, to cause a progressive decrease in the effective length of succeeding strokes of said plunger to compensate for the increasing volume of cork composition in said mold, a hopper adapted to receive cork composition, a valve shaft, a rotary measuring valve carried thereby, a shaft, means whereby movement is imparted to said shaft alternately in opposite direction in accordance with the movements of said slide, and operative connection between said last named shaft and said valve shaft, including therein a member carried by and movable with said valve shaft, a member idly mounted upon said valve shaft, cam shaped clutch members carried by said last named member, ratchet pins carried by said first named member, a pawl operative upon said first named member whereby unidirectional, intermittent movement is imparted to said valve, means adapted to maintain said ratchet pins out of the operative relation to said clutch members, means actuated after a predetermined number of strokes of said slide whereby said last named means may be actuated to make said pins inoperative, and upon the succeeding stroke of said slide permit said ratchet pins to be restored to their operative position, and connections between said last named shaft and said member idly mounted on the valve shaft.

20. A cork slab packing machine embodying therein a support for a mold, a plunger adapted to enter said mold, a reciprocatory slide, means whereby said slide receives uniform reciprocatory movement, means carried by said slide and adapted to operatively engage said plunger and to impart positive reciprocatory motion thereto, means whereby the operative relation between said last named means and said plunger will be automatically varied with each stroke of said slide and said plunger, to cause a progressive decrease in the effective length of succeeding strokes of said plunger to compensate for the increasing volume of cork composition in said mold, a hopper adapted to receive cork composition, a valve shaft, a rotary measuring valve carried thereby, a shaft, means whereby movement is imparted to said shaft alternately in opposite direction in accordance with the movements of said slide, and operative connection between said last named shaft and said valve shaft, including therein a member carried by and movable with said valve shaft, a member idly mounted upon said valve shaft, a pawl and ratchet mechanism limiting the movement of said member to one direction, a ratchet wheel idly mounted upon said valve shaft adjacent said last named member and having segmental slots therein with an enlarged portion at one point thereof, ratchet pins carried by said first named member but passing through, and having an enlarged head adapted to enter said enlarged portions of said slots, and to engage said wheel adjacent the other portions of said slots, cam shaped clutch members carried by said last named member co-operating with said pins,

a pawl normally disengaged from but adapted to operatively engage the teeth of said ratchet wheel, means actuated by, and after a predetermined number of strokes of, said 5 plunger, and operative upon said ratchet wheel, whereby said wheel is moved in relation to said pawl and said pins while said pins are out of the operative relation to said cams to maintain them out of the operative 10 relation to said cams and prevent actuation of said valve upon the succeeding stroke of said plunger, and connections between said last named shaft and said member idly mounted upon the valve shaft.

15 20. A cork slab packing machine embodying therein a support for a mold, a plunger adapted to enter said mold, a reciprocatory slide, means whereby said slide receives uniform reciprocatory movement, means carried 20 by said slide and adapted to operatively engage said plunger and to impart positive reciprocatory motion thereto, means whereby the operative relation between said last named means and said plunger will be automatically 25 varied with each stroke of said slide and said plunger, to cause a progressive decrease in the effective length of succeeding strokes of said plunger to compensate for the increasing volume of cork com- 30 position in said mold, a hopper adapted to receive cork composition, a valve shaft, a rotary measuring valve carried thereby, a chute extending from adjacent said valve to adjacent the open top of a mold, a gate 35 co-operating with said chute, a shaft, means whereby movement is imparted to said shaft alternately in opposite direction in accordance with the movements of said slide, operative connection between said last named 40 shaft and said valve shaft, including therein a member carried by and movable with said valve shaft, a member idly mounted upon said valve shaft, a pawl and ratchet mechanism limiting the movement of said member to one direction, a ratchet wheel idly mounted upon 45 said valve shaft adjacent said last named member and having segmental slots therein with an enlarged portion at one point thereof, ratchet pins carried by said 50 first named member but passing through, and having an enlarged head adapted to enter said enlarged portions of, said slots, and to engage said wheel adjacent the other portions of said slots, cam shaped clutch mem- 55 bers carried by said last named member co-operating with said pins, a pawl normally disengaged from but adapted to operatively engage the teeth of said ratchet wheel, means actuated by, and after a predetermined number of strokes of, said plunger, and operative upon said ratchet wheel, whereby said wheel is moved in relation to 60 said pawl and said pins while said pins are out of the operative relation to said cams to maintain them out of the operative rela- 65

tion to said cams and prevent actuation of said valve upon the succeeding stroke of said plunger, means adapted to move said wheel to a position where the enlarged heads of said pins may enter the enlarged 70 portions of said slots, means actuated by the means for moving said ratchet wheel adapted upon the succeeding stroke of said plunger to disengage the pawl co-operating with said wheel therefrom, whereby cork composition 75 will be fed upon the succeeding stroke of said plunger, and connections between said last named shaft and said member idly mounted upon the valve shaft, and means for positioning a closure plug above the open top of a mold and within the path of movement of said plunger whereby the last of a predetermined number of strokes of said plunger will force said plug in a mold.

21. A cork slab packing machine embodying 85 therein a support for a mold, a plunger adapted to enter said mold, a reciprocatory slide, means whereby said slide receives uniform reciprocatory movement, means carried by said slide and adapted to operatively engage said plunger and to impart positive reciprocatory motion thereto, means whereby the operative relation between said last named means and said plunger will be automatically 90 varied with each stroke of said slide and said plunger, to cause a progressive decrease in the effective length of succeeding strokes of said plunger to compensate for the increasing volume of cork composition in said mold, a hopper adapted to receive cork com- 95 position, a valve shaft, a rotary measuring valve carried thereby, a chute extending from adjacent said valve to adjacent the open top of a mold, a gate co-operating with said chute, a shaft, means whereby movement is imparted to said shaft alternately in 100 opposite direction in accordance with the movements of said slide, operative connection between said last named shaft and said valve shaft, including therein a member carried by and movable with said valve shaft, a member idly mounted upon said valve shaft, a pawl and ratchet mechanism limiting the movement of said member to one direction, a ratchet wheel idly mounted upon 105 said valve shaft adjacent said last named member and having segmental slots therein with an enlarged portion at one point thereof, ratchet pins carried by said first named member but passing through, and having an enlarged head adapted to enter said enlarged portions of, said slots, and to engage said wheel adjacent the other portions of said slots, cam shaped clutch mem- 110 bers carried by said last named member co-operating with said pins, a pawl normally disengaged from but adapted to operatively engage the teeth of said ratchet wheel, a lift rod, a tappet thereon positioned in the path of movement of said plunger and 115

120

125

130

adapted to be engaged thereby upon two succeeding strokes of said plunger when it has reached a predetermined position in relation to said slide, means actuated by said lift rod 5 adapted to operatively engage said ratchet wheel, whereby said wheel is moved in relation to said pawl and said pins while said pins are out of the operative relation to said cams to maintain them out of the operative 10 relation to said cams and prevent actuation of said valve upon the succeeding stroke of said plunger, means adapted to move said wheel to a position where the enlarged heads of said pins may enter the enlarged portions 15 of said slots, means actuated by the means for moving said ratchet wheel adapted upon the succeeding stroke of said plunger to disengage the pawl co-operating with said wheel, therefrom, whereby cork composition 20 will be fed upon the succeeding stroke of said plunger, and connections between said last named shaft and said member idly mounted upon the valve shaft, and means for positioning a closure plug above the 25 open top of a mold and within the path of movement of said plunger whereby the last of a predetermined number of strokes of said plunger will force said plug in a mold.

22. A cork slab packing machine embodying therein a support for a mold, a plunger adapted to enter said mold, a reciprocatory slide, means whereby said slide receives uniform reciprocatory movement, means carried by said slide and adapted to operatively engage said plunger and to impart positive reciprocatory motion thereto, means whereby the operative relation between said last named means and said plunger will be automatically varied with each stroke of 30 said slide and said plunger, to cause a progressive decrease in the effective length of succeeding strokes of said plunger to compensate for the increasing volume of cork composition in said mold, a hopper adapted 35 to receive cork composition, a valve shaft, a rotary measuring valve carried thereby, a chute extending from adjacent said valve to adjacent the open top of a mold, a gate co-operating with said chute, a shaft, means whereby movement is imparted to said shaft alternately in opposite direction in accordance with the movements of said slide, and operative connection between said last named shaft and said valve shaft, including there- 40 in a member carried by and movable with said valve shaft, a member idly mounted upon said valve shaft, a pawl and ratchet mechanism limiting the movement of said member to one direction, a ratchet wheel idly mounted upon said valve shaft adjacent said last named member and having seg- 45 mental slots therein with an enlarged portion at one point thereof, ratchet pins carried by said first named member but passing through, and having an enlarged head adapt- 50 ed to enter said enlarged portions of, said slots, and to engage said wheel adjacent the other portions of said slots, cam shaped clutch members carried by said last named member co-operating with said pins, a pawl 55 normally disengaged from but adapted to operatively engage the teeth of said ratchet wheel, a lift rod, a tappet thereon positioned in the path of movement of said plunger and adapted to be engaged thereby upon two 60 succeeding strokes of said plunger when it has reached a predetermined position in relation to said slide, a rocking lever, one arm of which is adapted to engage said tappet, a second rocking lever, means acted on by the other arm of said lever, and operative upon one arm of said second lever, a pawl pivotally mounted on the other arm of said second lever and in position to be normally 65 disengaged from, but adapted to be engaged with, said ratchet wheel, whereby said wheel is moved in relation to said pawl and said pins while said pins are out of the operative relation to said cams to maintain them 70 out of the operative relation to said cams and prevent actuation of said valve upon the succeeding stroke of said plunger, means adapted to move said wheel to a position where the enlarged heads of said pins may 75 enter the enlarged portions of said slots, means actuated by said second rocking lever adapted, upon the succeeding stroke of said plunger, to disengage the pawl co-operating with said wheel, therefrom, whereby cork composition will be fed upon the 80 succeeding stroke of said plunger, and connections between said last named shaft and said member idly mounted upon the valve shaft, and means for positioning a closure plug above the open top of a mold and within the path of movement of said plunger whereby the last of a predetermined number of strokes of said plunger will force said 85 plug in a mold.

23. A cork slab packing machine embodying therein a support for a mold, a plunger adapted to enter said mold, a reciprocatory slide, means whereby said slide receives uniform reciprocatory movement, means carried by said slide and adapted to operatively engage said plunger and to impart positive reciprocatory motion thereto, means whereby the operative relation between said last named means and said plunger will be automatically varied with each stroke of said 90 slide and said plunger, to cause a progressive decrease in the effective length of succeeding strokes of said plunger to compensate for the increasing volume of cork composition in said mold, a hopper adapted 95 to receive cork composition, a measuring valve, a chute extending from adjacent said valve to adjacent the open top of the mold, a vertically slid able gate adapted to engage the bottom of said chute, lugs carried by 100

105

110

115

120

125

130

said gate extending in the path of movement of said slide whereby upon each up stroke of said slide said gate will be opened, means actuated by the movement of said slide whereby said gate will be opened between succeeding down strokes of the plunger and slide, and means for intermittently actuating said valve.

24. A cork slab packing machine embodying therein a support for a mold, a plunger adapted to enter said mold, a reciprocatory slide, means whereby said slide receives uniform reciprocatory movement, means carried by said slide and adapted to operatively engage said plunger and to impart positive reciprocatory motion thereto, means whereby the operative relation between said last named means and said plunger will be automatically varied with each stroke of said slide and said plunger, to cause a progressive decrease in the effective length of succeeding strokes of said plunger to compensate for the increasing volume of cork composition in said mold, a hopper adapted to receive cork composition, a valve shaft, a rotary measuring valve carried thereby, a chute extending from adjacent said valve to adjacent the open top of a mold, a vertically slidable gate adapted to engage the bottom of said chute, lugs carried by said gate extending in the path of movement of said slide whereby upon each up stroke of said slide said gate will be opened, a shaft, means whereby movement is imparted to said shaft alternately in opposite direction in accordance with the movements of said slide, operative connection between said last named shaft and said valve shaft, including therein a member carried by and movable with said valve shaft, a member idly mounted upon said valve shaft, a pawl and ratchet mechanism limiting the movement of said member to one direction, a ratchet wheel idly mounted upon said valve shaft adjacent said last named member and having segmental slots therein with an enlarged portion at one point thereof, ratchet pins carried by said first named member but passing through, and having an enlarged head adapted to enter said enlarged portions of said slots, and to engage said wheel adjacent the other portions of said slots, cam shaped clutch members carried by said last named member co-operating with said pins, a pawl normally disengaged from but adapted to operatively engage the teeth of said ratchet wheel, means actuated by, and after a predetermined number of strokes of, said plunger, and operative upon said ratchet wheel, whereby said wheel is moved in relation to said pawl and said pins while said pins are out of the operative relation to said cams to maintain them out of the operative relation to said cams and prevent actuation of said valve upon the succeeding stroke of said plunger, means adapt-

ed to move said wheel to a position where the enlarged heads of said pins may enter the enlarged portions of said slots, means actuated by the means for moving said ratchet wheel adapted upon the succeeding stroke of said plunger to disengage the pawl co-operating with said wheel, therefrom, whereby cork composition will be fed upon the succeeding stroke of said plunger, and connections between said last named shaft and said member idly mounted upon the valve shaft, and means for positioning a closure plug above the open top of a mold and within the path of movement of said plunger whereby the last of a predetermined number of strokes of said plunger will force said plug in a mold.

25. A cork slab packing machine embodying therein a support for a mold, a plunger adapted to enter said mold, a reciprocatory slide, means whereby said slide receives uniform reciprocatory movement, means carried by said slide and adapted to operatively engage said plunger and to impart positive reciprocatory motion thereto, means whereby the operative relation between said last named means and said plunger will be automatically varied with each stroke of said slide and said plunger, to cause a progressive decrease in the effective length of succeeding strokes of said plunger to compensate for the increasing volume of cork composition in said mold, a hopper adapted to receive cork composition, a valve shaft, a rotary measuring valve carried thereby, means adapted to deliver cork composition fed by said valve into the open top of a mold, a shaft, means whereby movement is imparted to said shaft alternately in opposite direction in accordance with the movements of said slide, and operative connection between said last named shaft and said valve shaft, including therein a member carried by and movable with said valve shaft, a member idly mounted upon said valve shaft, cam shaped clutch members carried by said last named member, ratchet pins carried by said first named member, a pawl operative upon said first named member whereby unidirectional, intermittent movement is imparted to said valve, and connections between said last named shaft and said member idly mounted on the valve shaft.

26. A cork slab packing machine embodying therein a support for a mold, a plunger adapted to enter said mold, a reciprocatory slide, means whereby said slide receives uniform reciprocatory movement, means carried by said slide and adapted to operatively engage said plunger and to impart positive reciprocatory motion thereto, means whereby the operative relation between said last named means and said plunger will be automatically varied with each stroke of said slide and said plunger, to cause a pro-

gressive decrease in the effective length of succeeding strokes of said plunger to compensate for the increasing volume of cork composition in said mold, a hopper adapted 5 to receive cork composition, a valve shaft, a rotary measuring valve carried thereby, means adapted to deliver cork composition fed by said valve into the open top of a mold, a shaft, means whereby movement is 10 imparted to said shaft alternately in opposite direction in accordance with the movements of said slide, and operative connection between said last named shaft and said valve shaft, including therein a member carried by and movable with said valve shaft, a member idly mounted upon said valve shaft, cam shaped clutch members carried by said last named member, ratchet pins carried by said first named member, a pawl 15 operative upon said first named member whereby unidirectional, intermittent movement is imparted to said valve, means adapted to maintain said ratchet pins out of the operative relation to said clutch members, 20 means actuated after a predetermined number of strokes of said slide whereby said last named means may be actuated to make said pins inoperative, and upon the succeeding stroke of said slide permit said ratchet 25 pins to be restored to their operative position, and connections between said last named shaft and said member idly mounted on the valve shaft.

27. A cork slab packing machine embodying therein a support for a mold, a plunger adapted to enter said mold, a reciprocatory slide, means whereby said slide receives uniform reciprocatory movement, means carried by said slide and adapted to operatively engage said plunger and to impart positive reciprocatory motion thereto, means whereby the operative relation between said last named means and said plunger will be automatically varied with each stroke of 40 said slide and said plunger, to cause a progressive decrease in the effective length of succeeding strokes of said plunger to compensate for the increasing volume of cork composition in said mold, means delivering a measured quantity of cork composition to 45 within said mold prior to each stroke of the plunger inwardly of the mold, a support for a closure plug adjacent the open top of a mold, an oscillatory lever, means carried thereby in engaging relation with a plug, and means operative upon the last down stroke of said plunger whereby said lever will receive oscillatory movement to move a plug above the open top of the mold, in 50 the path of movement of said plunger.

28. A cork slab packing machine embodying therein a support for a mold, a plunger adapted to enter said mold, a reciprocatory slide, means whereby said slide receives uniform reciprocatory movement, means car-

ried by said slide and adapted to operatively engage said plunger and to impart positive reciprocatory motion thereto, means whereby the operative relation between said last named means and said plunger will be 70 automatically varied with each stroke of said slide and said plunger, to cause a progressive decrease in the effective length of succeeding strokes of said plunger to compensate for the increasing volume of cork 75 composition in said mold, means delivering a measured quantity of cork composition to within said mold prior to each stroke of the plunger inwardly of the mold, means making the means for delivering cork composition to within the mold inoperative to deliver cork composition to the mold upon the last stroke of said plunger, a support for a closure plug adjacent the open top of a mold, an oscillatory lever, means carried thereby in engaging relation with a plug, and means operative upon the last down stroke of said plunger whereby said lever will receive oscillatory movement to move a plug above the open top of the mold, in the 90 path of movement of said plunger.

29. A cork slab packing machine embodying therein a support for a mold, a plunger adapted to enter said mold, a reciprocatory slide, means whereby said slide receives uniform reciprocatory movement, means carried by said slide and adapted to operatively engage said plunger and to impart positive reciprocatory motion thereto, means whereby the operative relation between said last 100 named means and said plunger will be automatically varied with each stroke of said slide and said plunger, to cause a progressive decrease in the effective length of succeeding strokes of said plunger to compensate for the increasing volume of cork composition in said mold, means delivering a measured quantity of cork composition to within said mold prior to each stroke of the plunger inwardly of the mold, a support for a closure plug adjacent the open top of a mold, an oscillatory lever, means carried thereby in engaging relation with a plug, means operative upon the last down stroke of said plunger whereby said lever will receive oscillatory movement to move a plug above the open top of the mold, in the path 110 of movement of said plunger, and automatically acting means for stopping the machine after a predetermined number of strokes of 115 said plunger.

30. A cork slab packing machine embodying therein a support for a mold, a plunger adapted to enter said mold, a reciprocatory slide, means whereby said slide receives uniform reciprocatory movement, means carried by said slide and adapted to operatively engage said plunger and to impart positive reciprocatory motion thereto, means whereby the operative relation between said last 120 125 130

- named means and said plunger will be automatically varied with each stroke of said slide and said plunger, to cause a progressive decrease in the effective length of succeeding strokes of said plunger to compensate for the increasing volume of cork composition in said mold, means delivering a measured quantity of cork composition to within said mold prior to each stroke of the plunger inwardly of the mold, means making the means for delivering cork composition to within the mold inoperative to deliver cork composition to the mold upon the last stroke of said plunger, a support for a closure plug adjacent the open top of a mold, an oscillatory lever, means carried thereby in engaging relation with a plug, means operative upon the last down stroke of said plunger whereby said lever will receive oscillatory movement to move a plug above the open top of the mold, in the path of movement of said plunger, an automatically acting means for stopping the machine after a predetermined number of strokes of said plunger.
31. A cork slab packing machine embodying therein a support for a mold, a plunger adapted to enter said mold, a reciprocatory slide, means whereby said slide receives uniform reciprocatory movement, means carried by said slide and adapted to operatively engage said plunger and to impart positive reciprocatory motion thereto, means whereby the operative relation between said last named means and said plunger will be automatically varied with each stroke of said slide and said plunger, to cause a progressive decrease in the effective length of succeeding strokes of said plunger to compensate for the increasing volume of cork composition in said mold, means delivering a measured quantity of cork composition to within said mold prior to each stroke of the plunger inwardly of the mold, a support for a closure plug adjacent the open top of a mold, an oscillatory lever, means carried thereby in engaging relation with a plug, centering members adapted to act upon opposite ends of a plug and normally disengaged therefrom, means actuating said centering members, means operative upon the last down stroke of said plunger whereby said lever will receive oscillatory movement to move a plug above the open top of the mold, in the path of movement of said plunger, and automatically acting means for stopping the machine after a predetermined number of strokes of said plunger.
32. A cork slab packing machine embodying therein a support for a mold, a plunger adapted to enter said mold, a reciprocatory slide, means whereby said slide receives uniform reciprocatory movement, means carried by said slide and adapted to operatively engage said plunger and to impart positive reciprocatory motion thereto, means whereby the operative relation between said last named means and said plunger will be automatically varied with each stroke of said slide and said plunger, to cause a progressive decrease in the effective length of succeeding strokes of said plunger to compensate for the increasing volume of cork composition in said mold, means delivering a measured quantity of cork composition to within said mold prior to each stroke of the plunger inwardly of the mold, a support for a closure plug adjacent the open top of a mold, an oscillatory lever, means carried thereby in engaging relation with a plug, centering members adapted to act upon opposite ends of a plug and normally disengaged therefrom, means actuating said centering members, and means operative upon the last down stroke of said plunger whereby said lever will receive oscillatory movement to move a plug above the open top of the mold, in the path of movement of said plunger.
33. A cork slab packing machine embodying therein a support for a mold, a plunger adapted to enter said mold, a reciprocatory slide, means whereby said slide receives uniform reciprocatory movement, means carried by said slide and adapted to operatively engage said plunger and to impart positive reciprocatory motion thereto, means whereby the operative relation between said last named means and said plunger will be automatically varied with each stroke of said slide and said plunger, to cause a progressive decrease in the effective length of succeeding strokes of said plunger to compensate for the increasing volume of cork composition in said mold, means delivering a measured quantity of cork composition to within said mold prior to each stroke of the plunger inwardly of the mold, a support for a closure plug adjacent the open top of a mold, an oscillatory lever, a push rod carried thereby in engaging relation with a plug, a latch member slidably mounted upon said push rod adapted to be held against movement therewith, said latch member being adapted to engage a plug and hold it in fixed relation to the open top of the mold, means carried by said push rod and co-operating with said support for a closure plug, whereby said latch member will be disengaged from the plug upon the initial movement of said push rod, and means operative upon the last down stroke of said plunger whereby said lever will receive oscillatory movement to move a plug above the open top of the mold, in the path of movement of said plunger.
34. A cork slab packing machine embodying therein a support for a mold, a plunger

adapted to enter said mold, a reciprocatory slide, means whereby said slide receives uniform reciprocatory movement, means carried by said slide and adapted to operatively engage said plunger and to impart positive reciprocatory motion thereto, means whereby the operative relation between said last named means and said plunger will be automatically varied with each stroke of said slide and said plunger, to cause a progressive decrease in the effective length of succeeding strokes of said plunger to compensate for the increasing volume of cork composition in said mold, means delivering a measured quantity of cork composition to within said mold prior to each stroke of the plunger inwardly of the mold, means making the means for delivering cork composition to within the mold inoperative to deliver cork composition to the mold upon the last stroke of said plunger, a support for a closure plug adjacent the open top of a mold, an oscillatory lever, a push rod carried thereby in engaging relation with a plug, a latch member slidably mounted upon said push rod adapted to be held against movement therewith, said latch member being adapted to engage a plug and hold it in fixed relation to the open top of the mold, means carried by said push rod and cooperating with said support for a closure plug, whereby said latch member will be disengaged from the plug upon the initial movement of said push rod, means operative upon the last down stroke of said plunger whereby said lever will receive oscillatory movement to move a plug above the open top of the mold, in the path of movement of said plunger, and automatically acting means for stopping the machine after a predetermined number of strokes of said plunger.

35. A cork slab packing machine embodying therein a support for a mold, a plunger adapted to enter said mold, a reciprocatory slide, means whereby said slide receives uniform reciprocatory movement, means carried by said slide and adapted to operatively engage said plunger and to impart positive reciprocatory motion thereto, means whereby the operative relation between said last named means and said plunger will be automatically varied with each stroke of said slide and said plunger, to cause a progressive decrease in the effective length of succeeding strokes of said plunger to compensate for the increasing volume of cork composition in said mold, a hopper adapted to receive cork composition, a valve shaft, a rotary measuring valve carried thereby, means whereby cork composition delivered by said valve is discharged through the open top of a mold, means whereby intermittent unidirectional movement is imparted to said valve shaft, lift rods adapted to be engaged by said plunger when it has reached a predetermined position in relation to said slide, operative connections between one of said lift members and the means for actuating said valve shaft, whereby said means will be made inoperative to feed cork composition upon next to the last down stroke of said plunger, latch members controlled by said lift rods respectively, centering members carried by said latch members, normally disengaged from, and adapted to act upon opposite ends of a plug, a support for a plug adjacent the open top of a mold, an oscillatory lever, means carried thereby in engaging relation with a plug, a dog carried by the other arm of said lever, a hooked member carried by said valve shaft, means normally maintaining said dog out of the operative relation to said hooked member, and a rocking lever, one arm of which is operative upon said dog, and the other arm of which operatively engages one of said lift rods, whereby said dog will be engaged with said hooked member upon the final down stroke of said plunger to move a plug above the open top of the mold, in the path of movement of said plunger, said centering

cent the open top of a mold, an oscillatory lever, means carried thereby in engaging relation with a plug, a dog carried by the other arm of said lever, a hooked member carried by said valve shaft, means normally maintaining said dog out of the operative relation to said hooked member, means operative upon said dog, and means actuated by said plunger and operative upon said last named means whereby said dog will be engaged with said hooked member upon the final down stroke of said plunger to move a plug above the open top of the mold, in the path of movement of said plunger.

36. A cork slab packing machine embodying therein a support for a mold, a plunger adapted to enter said mold, a reciprocatory slide, means whereby said slide receives uniform reciprocatory movement, means carried by said slide and adapted to operatively engage said plunger and to impart positive reciprocatory motion thereto, means whereby the operative relation between said last named means and said plunger will be automatically varied with each stroke of said slide and said plunger, to cause a progressive decrease in the effective length of succeeding strokes of said plunger to compensate for the increasing volume of cork composition in said mold, a hopper adapted to receive cork composition, a valve shaft, a rotary measuring valve carried thereby, means whereby cork composition delivered by said valve is discharged through the open top of a mold, means whereby intermittent unidirectional movement is imparted to said valve shaft, lift rods adapted to be engaged by said plunger when it has reached a predetermined position in relation to said slide, operative connections between one of said lift members and the means for actuating said valve shaft, whereby said means will be made inoperative to feed cork composition upon next to the last down stroke of said plunger, latch members controlled by said lift rods respectively, centering members carried by said latch members, normally disengaged from, and adapted to act upon opposite ends of a plug, a support for a plug adjacent the open top of a mold, an oscillatory lever, means carried thereby in engaging relation with a plug, a dog carried by the other arm of said lever, a hooked member carried by said valve shaft, means normally maintaining said dog out of the operative relation to said hooked member, and a rocking lever, one arm of which is operative upon said dog, and the other arm of which operatively engages one of said lift rods, whereby said dog will be engaged with said hooked member upon the final down stroke of said plunger to move a plug above the open top of the mold, in the path of movement of said plunger, said centering

members having wedge-shaped heads adapted to enter wedge-shaped recesses in said plug, whereby as said plug passes said centering members, said latches, said centering members, said lift rods and the mechanisms actuated thereby will be restored to their normal positions.

inwardly of the mold, a lift rod, means whereby said rod is actuated when said plunger has reached a predetermined position in relation to said slide, a clutch mechanism controlling the operation of said means imparting reciprocatory movement to said shaft, a shift bar controlling said clutch mechanism, a latch member, operative connections between said latch member and said lift rod, an impact member controlled by said latch member and adapted to have movement toward and from the means for imparting reciprocatory movement to said slide, a clutch member slidably mounted upon said shift bar, said shift bar having a clutch surface co-operating therewith, a spring tending to normally engage said clutch member with said clutch surface, flexible connections between said clutch member and said impact member, and a tappet upon said crank wheel adapted by engagement with said impact member to actuate said last named clutch member and said shift bar to release said clutch mechanism.

39. A cork slab packing machine embodying 90
therein a support for a mold, a plunger
adapted to enter said mold, a reciprocator
slide, a crank wheel, a pitman connection
between said crank wheel and said slide
whereby said slide receives uniform reciprocator
movement, means carried by said 95
slide and adapted to operatively engage said
plunger and to impart positive reciprocator
motion thereto, means whereby the operative
relation between said last named means
and said plunger will be automatically
varied with each stroke of said slide and
said plunger, to cause a progressive decrease
in the effective length of succeeding strokes
of said plunger to compensate for the in- 100
creasing volume of cork composition in said
mold, means delivering a measured quantity
of cork composition to within said mold
prior to each stroke of the plunger inwardly
of the mold, a lift rod, means whereby said 105
rod is actuated when said plunger has
reached a predetermined position in relation
to said slide, a clutch mechanism controlling
the operation of said means imparting 110
reciprocator movement to said shaft, a
shift bar controlling said clutch mechanism,
a latch member, operative connections be- 115
tween said latch member and said lift rod,
an impact member controlled by said latch
member and adapted to have movement to- 120
ward and from the means for imparting re-
ciprocator movement to said slide, a clutch
member slidably mounted upon said shift
bar, said shift bar having a clutch surface co- 125
operating therewith, a spring tending to nor-
mally engage said clutch member with said
clutch surface, flexible connections between
said clutch member and said impact member,
a tappet upon said crank wheel adapted by 130
engagement with said impact member to ac-

tuate said last named clutch member and said shift bar to release said clutch mechanism, manually operative means for actuating said shift bar, manually operative means where-
5 by said lift rod may be actuated to cause movement of said impact member, and a second tappet carried by said crank wheel, so set as to actuate said impact member before said slide has been raised by said pit-
10 man to the limit of its upward stroke.

40. A cork slab packing machine embodying therein a support for a mold, a plunger adapted to enter said mold, a reciprocatory slide, a crank wheel, a pitman connection
15 between said crank wheel and said slide whereby said slide receives uniform reciprocatory movement, means carried by said slide and adapted to operatively engage said plunger and to impart positive reciprocatory
20 motion thereto, means whereby the operative relation between said last named means and said plunger will be automatically varied with each stroke of said slide and said plunger, to cause a progressive decrease
25 in the effective length of succeeding strokes of said plunger to compensate for the increasing volume of cork composition in said mold, means delivering a measured quantity of cork composition to within said mold
30 prior to each stroke of the plunger inwardly of the mold, a lift rod, means whereby said rod is actuated when said plunger has reached a predetermined position in
35 relation to said slide, a clutch mechanism controlling the operation of said means imparting reciprocatory movement to said shaft, a shift bar controlling said clutch mechanism, a latch member, operative connections between said latch member and said
40 lift rod, an impact member controlled by said latch member and adapted to have movement toward and from the means for imparting reciprocatory movement to said slide, a clutch member slidably mounted
45 upon said shift bar, said shift bar having a clutch surface co-operating therewith, a spring tending to normally engage said clutch member with said clutch surface, flexible connections between said clutch
50 member and said impact member, a tappet upon said crank wheel adapted by engagement with said impact member to actuate said last named clutch member and said shift bar to release said clutch mechanism, manually operative means for actuating said shift bar, manually operative means whereby said lift rod may be actuated to cause movement of said impact member, a second tappet carried by said crank wheel,
55 so set as to actuate said impact member before said slide has been raised by said pitman to the limit of its upward stroke, and a rocking lever, one arm of which is adapted to enter a shouldered recess in said shift bar and the other arm of which is adapted to be engaged by said lift rod, said recess in said shift bar being so positioned as to receive said rocking lever only when said clutch is released.

41. A cork slab packing machine embodying therein a support for a mold, a plunger adapted to enter said mold, a reciprocatory
60 slide, a crank wheel, a pitman connection

between said crank wheel and said slide whereby said slide receives uniform reciprocatory movement, means carried by said slide and adapted to operatively engage said plunger and to impart positive reciprocatory motion thereto, means whereby the operative relation between said last named means and said plunger will be automatically varied with each stroke of said slide and said plunger, to cause a progressive decrease
75 in the effective length of succeeding strokes of said plunger to compensate for the increasing volume of cork composition in said mold, means delivering a measured quantity of cork composition to within said mold prior to each stroke of the plunger inwardly of the mold, a lift rod, means whereby said rod is actuated when said plunger has reached a predetermined position in
80 relation to said slide, a clutch mechanism controlling the operation of said means imparting reciprocatory movement to said shaft, a shift bar controlling said clutch mechanism, a latch member, operative connections between said latch member and said lift rod, an impact member controlled by said latch member and adapted to have movement toward and from the means for imparting reciprocatory movement to said slide, a clutch member slidably mounted
85 upon said shift bar, said shift bar having a clutch surface co-operating therewith, a spring tending to normally engage said clutch member with said clutch surface, flexible connections between said clutch
90 member and said impact member, a tappet upon said crank wheel adapted by engagement with said impact member to actuate said last named clutch member and said shift bar to release said clutch mechanism, 100
95 manually operative means for actuating said shift bar, manually operative means whereby said lift rod may be actuated to cause movement of said impact member, a second tappet carried by said crank wheel,
105 so set as to actuate said impact member before said slide has been raised by said pitman to the limit of its upward stroke, and a rocking lever, one arm of which is adapted to enter a shouldered recess in said shift bar and the other arm of which is adapted to be engaged by said lift rod, said recess in said shift bar being so positioned as to receive said rocking lever only when said clutch is released.

42. A cork slab packing machine embodying therein a support for a mold, a plunger adapted to enter said mold, a reciprocatory slide, means whereby said slide receives uniform reciprocatory movement, means carried by said slide and adapted to operatively engage said plunger and to impart positive reciprocatory motion thereto, means whereby the operative relation between said last named means and said plunger will be
125
130

automatically varied with each stroke of said slide and said plunger, to cause a progressive decrease in the effective length of succeeding strokes of said plunger to 5 compensate for the increasing volume of cork composition in said mold, pivoted clamp bars adapted to engage the mold upon said support and hold it with its cavity in alinement with said plunger, pivotally 10 mounted links, clamps carried by said links in engaging relation with said clamp bars, and means delivering a measured quantity of cork composition to within said mold prior to each stroke of the plunger inwardly of the mold. 15

In witness whereof I have hereunto affixed my signature this 12th day of November, 1923.

CHARLES E. McMANUS.
